JOSEPH V. O'CONNOR, OF CUYAHOGA FALLS, OHIO, ASSIGNOR TO RICHARD J. O'CONNOR,
OF CUYAHOGA FALLS, OHIO

WINDOW CONSTRUCTION

Application filed June 14, 1930. Serial No. 461,155.

This invention relates to an improved window construction which is characterized by an improved sill which is especially designed to compensate for drainage of water so as to prevent rain water from getting into the interior of the house by way of the sill.

It is a matter of common knowledge that rain water when dashed against the members of the window frame gravitates down to the bottom of the members and accumulates on the sill. The excess water naturally runs off on the outside of the sill, jamb, sash and to the outside edge of the sill, and drops off without harm. A certain percentage of the water however seeps into the groove at the opposite end of the sill and finds its way into the interior of the house, frequently soaking the wall plaster and ruining the wallpaper.

The primary distinguishable structural features are embodied in the shape and configuration of the sill which co-operates with adjacent parts of the window frame proper to provide more dependable weather-proof joints.

The specific details and their relative arrangement and association will become more readily apparent from the following description and drawings.

In the drawings:
Figure 1 is a vertical sectional view through the sill showing the abutting relationship of the complementary parts of the sash and frame.

Figure 2 is a sectional view taken approximately on the plane of the line 2-2 of Figure 4.

Figure 3 is a top plan view of the sill.

Figure 4 is a horizontal sectional view taken on the plane of the line 4-4 of Figure 1.

Figure 5 is a perspective cross section on the line 5-5 of Figure 3.

Figure 6 is a detail sectional view on the line 6-6 of Figure 2.

The improved sill is generally represented by the numeral 7 and is characterized by a number of different features. For instance at the opposite end are grooves 8 for reception of the lower end portion of the jamb 9. In accordance with the present invention

there is a counter groove 10 of V-shaped configuration formed in the bottom of the main groove 8, and this communicates with an adjacent inclined drain passage 11 whose discharge end is located adjacent the outer edge 55 of the body of the sill.

Formed across the bottom of the sill is a trough 12. Formed on top of the sill is a shoulder 13 and a similar shoulder raised portion is formed at 14. The last named shoulder 14 is adapted for reception in a mortise groove formed in the bottom of the stool 15 as shown in Figure 1. This provides a dependable weatherproof joint at this point.

Underneath this mortise joint is a longitudinal rabbet 16 which is provided to unite the plaster and lathing with the sill member so that this excludes the air or wind from reaching the inside at this particular point. In accordance with the invention the lower end of the jamb in each instance is cut off so that it seats in the main groove 8 as shown in Figure 2 and overlies the V-shaped counter-groove 10 as shown in Figure 6. Thus the water which seeps down along the jamb collects in the groove 10 and gravitates down through the passage 11 where it is deposited.

Referring to Figure 4, it will be observed that the numeral 17 designates the parting strip carried by the jamb 9, and it will be noted that the blind stop 18 located adjacent this is formed with a vertical groove for reception of a tongue 19 on the jamb providing a weatherproof joint at this particular point.

The outside casing or facing board 20 has its lower end extended down below the top of the body of the sill so as to engage behind the aforesaid shoulder 13, thus providing another weatherproof joint here. The numeral 21 merely designates the studding and 22 the plaster, siding or the like.

The structural details to be emphasized are as follows:

First, I call attention to the manner in which the lower end portions of the jambs 9 are seated in the grooves 8 so as to permit these ends to overly the V-shaped counter-groove 10. This allows the water which ac-

cumulates at this point to gravitate down through the countergroove 10 and to escape by way of the drain passages or ports 11.

The shoulder 14 at the inner longitudinal edge portion of the sill is important in that it provides a weatherproof joint with the complementary groove in the stool 15. Then too, the utilization of the rabbet 16 provides a desirable connection of the sill with the adjacent structure.

The tongue and groove joint between the parts 18 and 19 in Figure 4 is important to guard against the entrance of rain. Moreover, the projecting lower end portion of the outer casing board 20 co-operating with the adjacent shoulder 13 is an added feature. All of these features contribute toward the production of a practical and dependable window construction which is regarded as a novel contribution to the art and a decided improvement upon present day window constructions with which I am familiar.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice if desired.

I claim:

- 35 1. A window sill having a reduced outer part forming a shoulder at the junction of said reduced part and the main part of the sill, said shoulder being located on the upper face of the sill, and said sill having transverse grooves in its upper face adjacent the ends thereof, said grooves terminating inwardly of the shoulder with the bottom of the grooves sloping upwardly and inwardly to the inner edge of the sill, said grooves receiving the lower ends of the side members of the frame, and the bottom of each of these grooves having a groove therein of less width than the first groove and said sill having drain openings therein sloping downwardly and outwardly from the outer ends of the second grooves through the lower face of the sill, and a longitudinally extending groove in the lower face of the sill spaced inwardly from the discharge end of the drain hole.
- 40 2. A window structure of the class described comprising a sill having transverse grooves therein, and a reduced outer part forming a shoulder on the upper face of the sill at the junction of the reduced part with the main part of the sill, side members having their lower ends seated in the grooves, the outer edges of the side members having ribs thereon, vertical strips having grooves therein for receiving the ribs, and exterior casing members having their lower ends abut-

ting the shoulder and portions of the inner faces abutting the strips, the transverse grooves terminating short of the shoulder with the lower ends of the strip resting on those portions of the sill between the outer ends of the grooves and the shoulder.

In testimony whereof I affix my signature.

JOSEPH V. O'CONNOR.
